UNITED STATES PATENT OFFICE.

HENRY MAHRER, OF MILNOR, NORTH DAKOTA.

GRAIN-SEPARATOR.

1,220,657.

Specification of Letters Patent   Patented Mar. 27, 1917.

Application filed June 16, 1916.   Serial No. 104,010.

To all whom it may concern:

Be it known that I, HENRY MAHRER, a citizen of the United States, residing at Milnor, in the county of Sargent, State of North Dakota, have invented certain new and useful Improvements in Grain-Separators; and I do hereby declare the following to be a full, clear, and exact description of the invention, such as will enable others skilled in the art to which it appertains to make and use the same.

This invention relates to grain separators and has special reference to a grain separator designed particularly for separating the wild oats from a mixture of wild and cultivated oats.

One object of the invention is to provide an improved general construction for devices of this character which will effectively separate the wild from the cultivated oats while at the same time being economical in construction and of few and simple parts so that the device will not readily get out of order.

A second object of the invention is to provide an improved means for feeding different classes of grain to a separator belt so that all of the grain will come in contact with the belt and will enable the belt to pick up the grain belonging to a certain class or classes, arrangement being made to cause such grain to adhere to the belt.

Another object of the invention is to provide means in connection with an inclined endless belt having a fleecy surface whereby the mixture of wild and cultivated oats may be fed across the path of movement of the belt in such manner that all of the wild oats will come in contact with the fleecy surface so that the barbs or beards of the wild oats will engage in the fleece and thus be carried along by the belt.

A further important object of the invention is to provide effective means for separating and disposing of the engaged grain after the same has been taken up by the belt.

Another object is to provide a novel form of scraper for use in connection with a device of this character.

With the above and other objects in view, as will be hereinafter apparent the invention consists in general of certain novel details of construction and combinations of parts hereinafter fully described, illustrated in the accompanying drawing, and specifically claimed.

In the accompanying drawings, like characters of reference indicate like parts in the several views, and:—

Figure 1 is a front elevation of a separator 60 constructed in accordance with this invention;

Fig. 2 is a rear elevation thereof;

Fig. 3 is a side elevation thereof;

Fig. 4 is a section on the line 4—4 of 65 Fig. 1;

Fig. 5 is an enlarged detail view taken in section through the grain feeding spout and showing its relation to the belt.

In the embodiment of the invention here- 70 in illustrated there is disclosed a main frame consisting of a pair of side members 10 which are held in fixed spaced relation by suitable bolts or spreaders 11. Pivoted at 12 to this main frame is a pair of struts or 75 legs 13 and these legs are connected at their lower ends to the side members by adjusting bolts 14 so that the bottoms of the legs may be drawn closer to or allowed to move farther away from the bottoms of the side mem- 80 bers whereby the inclination of the side members to the horizontal may be varied.

In the side members are formed oppo- 85 sitely disposed slots, the slots at the top being indicated at 15 while the slots at the bottom are indicated at 16. An operating pulley or roller 17 is provided and this pulley has journals 18 which fit in the slots 15 and are supported in said slots on bear- 90 ings 19 which rest on springs 20 held in the bottoms of the slots. Attached to this operating pulley is a crank or belt pulley handle 21 so that the pulley may be revolved. A similar pulley 22 provided with journals 23 is mounted in the slots 16. Trained over the 95 pulleys 17 and 22 is a belt which preferably is provided with a canvas or other like body for the purpose of giving strength and wear- 100 ing qualities and has a fleecy surface, the body being indicated at 24 and the surface 105 at 25. This belt is of such length that the springs 20 are compressed somewhat when the belt is in position and thus the springs tend to hold the belt at all times taut. Ex- 110 tendsing between the side members 10 and in contact with the under surface of the upper flight of the belt is a platen 26 which prevents sagging of this upper surface.

At 27 is a hopper and this hopper is preferably fixed to one of the side members 110 10 at a convenient height to receive the grain before separation. Leading diagonally

downward from the hopper and extending across the upper flight of the belt is a delivery spout indicated in general at 28. This spout is provided with an open side and the 5 remaining side of the spout is preferably made of tin. The bottom of the spout is preferably made of wood and is so formed as to be inclined to the surface of the belt so that grain passing down the spout will 10 be thrown toward the surface. This bottom is at all times in contact with the surface of the belt and thus the mixed wild and cultivated oats will all be fed diagonally across the upper flight of the belt. By this arrangement the barbs or beards on the wild 15 oats will engage the fleecy surface of the belt and adhere thereto so that as the upper flight of the belt moves upward the wild oats will be separated from the cultivated 20 oats. The cultivated oats will then pass downward along the spout and be delivered from the lower end thereof while the wild oats will be carried over the top pulley or roller and pass downward on the lower or 25 rear flight of the belt.

For the purpose of detaching or separating these wild oats from the belt there is provided a scraper and this scraper is of novel form. This scraper consists of a metallic plate having an end at right angles to the side. This end forms a scraping edge 29 while the sides 30 are secured to the legs 13 and extend downward along said legs. The bottom end of the scraper is cut 35 off diagonally and this end is bent backward toward the body of the scraper so as to form a diagonally extending delivery trough 31. By this means when the wild oats are passed downward on the rear or bottom flight of the belt the edge 29 detaches them from the belt and they drop down the plates to the delivery spout 31 from whence they pass off the bottom of this spout to a suitable receptacle.

40 It will thus be seen that by the above construction wild and cultivated oats may be readily separated, the one from the other, and that the device will be efficacious as all of the oats will be treated.

45 There has thus been provided a simple and efficient device of the kind described and for the purpose specified.

It is obvious that many minor changes 50 may be made in the form and construction of the invention without departing from the

material principles thereof. It is not therefore desired to confine the invention to the exact form herein shown and described but it is wished to include all such as properly come within the scope claimed. 60

What is claimed is:

1. In a device for separating grain, an endless belt having a surface to which a certain portion of the grain will adhere, pulleys supporting the belt, a driving device for one of the pulleys, an open sided feed spout extending diagonally across the front of the belt with the open side facing the belt and the bottom in contact therewith, and means to remove the adherent grain from the belt arranged in spaced relation to the feed spout. 65 70

2. In a device for separating grain, an endless belt having a surface to which a certain portion of the grain will adhere, said belt being arranged at an angle to the horizontal, a feed spout extending diagonally downward across the upper flight of the belt, said spout having the side next the belt open and having its bottom in contact with the belt and at an angle across the belt surface. 75 80

3. In a device for separating grain, an endless belt having a surface to which a certain portion of the grain will adhere, 85 said belt being arranged at an angle to the horizontal, a feed spout extending diagonally downward across the upper flight of the belt, said spout having the side next the belt open and having its bottom in contact with the belt and at an angle across the belt surface, and means beneath the upper flight of the belt arranged to hold the belt in engagement with the spout. 90 95

4. A scraper element for grain separators 95 employing a belt, comprising a plate of metal having one end and the sides at right angles to each other, said end being adapted for engagement with the belt to scrape grain therefrom, the lower end of said plate being diagonally disposed with respect to the sides and being bent back toward the body of the plate to form a trough. 100

In testimony whereof, I affix my signature in the presence of two witnesses.

HENRY MAHRER.
